SKIVING MACHINE

Leslie Hugh Bennion and William Arnold Smart,
Leicester, England, assignors to United Shoe
Machinery Corporation, Flemington, N. J., a
corporation of New Jersey

Application May 9, 1944, Serial No. 534,754
In Great Britain April 23, 1943

14 Claims. (Cl. 12-63).

This invention relates to improvements in or relating to splitting, skiving or like machines and is particularly, but by no means exclusively, concerned with machines (such as described in the patent to W. J. Young, No. 1,033,366) adapted for skiving boot or shoe stiffener blanks during the manufacture of stiffeners for use in stiffening heel end portions of boots or shoes. Such heel end stiffeners are frequently also known in the shoe manufacturing industry as counters.

By way of example, there is hereinafter described one convenient construction of machine which is provided by the invention and is illustrative thereof, the illustrative machine being an improved stiffener skiving machine having a horizontal matrix roll, a horizontal cooperating feed roll below the matrix roll, a horizontal fixed knife arranged along the discharge side of the bite of said rolls, devices or pressure fingers adapted to press a work piece into a matrix in the matrix roll and power means for controlling said devices.

Stiffener blanks for heel end portions of boots or shoes are usually cut out from sheet material (e. g., fibrous board material manufactured on paper making principles) to a desired shape and size and the margins of the blanks are then usually skived to provide a relatively thin edge around each blank before the blank is molded to the desired shape.

Machines by means of which stiffener blanks for heel end portions of boots or shoes have frequently hitherto been skived comprise a fixed knife, two cooperating rolls comprising a feed roll adapted to feed a blank to the knife and a cooperating matrix roll having formed in it a matrix of the same size as the blank and so formed that, as a blank passing between the rolls or from the line of feed or bite of the rolls, is pressed into the matrix and is fed to the knife, the knife, by a cut extending from one end of the blank to the other end, cuts from the blank a portion thereof, of wedge shaped cross section, extending all around the margin of the blank and the blank has thus formed on it a skived marginal portion having a relatively thin edge and a center portion which is not operated upon by the knife.

Skiving machines so arranged and adapted to skive such stiffener blanks have in some instances been provided with fingers associated with the feed roll which are arranged to press the blank into the matrix. These fingers are positioned in grooves extending around the feed roll and are urged toward the matrix roll by springs.

We have found, however, that such fingers, as

heretofore arranged, are not in all instances effective in pressing the blanks with sufficient firmness into the matrix. If the thickness of a blank has been slightly less than the depth of the matrix, the range of movement of the fingers has been found insufficient to press such a blank firmly therein.

If the blank is not pressed with sufficient firmness into the matrix, more especially the center portion of the blank, the knife edge as it is passing out of the blank at the center portion thereof when operating on the leading end portion of the blank and skiving the margin around the leading end portion thereof, is in some instances, especially if the blank has been cut from board, apt to tear the material at the center portion, instead of cutting out cleanly therefrom, and would thus spoil the blank. Hitherto, moreover, whether or not such tearing as referred to has occurred there has been a tendency when heel end stiffener blanks have been skived by machines of the character in question for the skiving result obtained at the leading end portion of a blank to differ appreciably from that obtained at the trailing end portion, a result which is undesirable.

According to one feature of the present invention a series of pressure fingers within grooves of a feed roll are provided which function to press a portion of the moving work into the matrix, the series of fingers having unitary means for controlling their range of operation which range may extend within the matrix without contacting the matrix roll at any time, and each pressure finger having supplementary means to control its own range and pressure of operation and each finger having easily accessible adjustment means.

Another feature of the invention is the provision of a mechanism comprising the pressure fingers, springs for actuating the pressure fingers, and control and adjustment means for the pressure fingers all mounted so as to be easily removable from the skiving machine as a unit.

Still another feature of the invention is the provision of mechanism and means in which a clearance may be maintained at all times between the pressure fingers and the contour of the matrix roll.

A further feature is a simple cam construction by means of which the pressure fingers are prevented from interfering with the introduction of the leading edge of a work piece to the bite between the feed roll and the matrix roll.

These and other features of the invention, including certain details of construction and com-

binations of parts will be described as embodied in an illustrated machine.

Referring to the accompanying drawings,

Fig. 1 is a sectional elevation of the illustrative machine;

Fig. 2 is a sectional plan view taken just above the pressure fingers with which the machine is provided;

Fig. 3 is a section taken along the line III—III of Fig. 1;

Fig. 4 is a section taken along the line IV—IV of Fig. 1;

Fig. 5 is a plan view of a magazine and blank feeding member;

Fig. 6 is a front view of the parts seen in Fig. 5; and

Fig. 7 is a sectional view showing a modified cam control for the pressing fingers.

The illustrated machine, having main parts similar to those shown in the machine of the Young Patent No. 1,033,366, above mentioned, comprises a main frame 10 in which is rotatably mounted a horizontal cylindrical matrix roll 12, a horizontal cylindrical feed roll 14 arranged below the matrix roll and a horizontal, fixed skiving knife 16 positioned on the discharge side of the bite between the rolls 12 and 14 arranged to skive a stiffener blank as it is being fed between the rolls. Power is imparted to a countershaft 1 (Fig. 1) by means not shown, and a pinion gear 3 affixed thereto drives a large gear 5 which in turn rotates a shaft 7 and the feed roll 14 and also the matrix roll 12, the latter by means of a gear 9 in mesh with a gear (not shown) on the shaft of roll 12. The rolls 12 and 14 are arranged to be driven in opposite directions as shown by the arrows and at the same peripheral speed. The feed roll 14 is urged upwardly toward the matrix roll 12 by means of springs 18. Only one spring 18 is shown (Fig. 1) but it is to be understood that a spring 18 is located at each end of the feed roll to urge bearing blocks 20 and the feed roll 14 upwardly in a conventional manner. Each spring 18 rests upon the main frame 10 and is maintained in place by means of rods 22 which are held in correct adjustment by means of nuts 24. Each nut 24 is held against rotation by a locking device comprising a yoke 26 adjustably secured upon a pin 28 by nuts 30 and 32.

The matrix roll 12 has formed in it a matrix 34 which is the same shape as the shape of a stiffener blank to be skived and has a center portion of a depth corresponding to the thickness of the blank and a marginal portion extending around the matrix which is inclined from the bottom of the matrix to the outer cylindrical face of the matrix roll 12. As a blank is fed from a magazine feeder 36 and between the rolls 12 and 14 to the knife 16, the blank is pressed into the matrix 34 and a marginal portion of the blank which is caused by the inclined portion of the matrix to project beyond the cylindrical portions of the matrix roll at each side and between the ends of the matrix is skived from the blank by the knife 16, leaving the marginal portion of the blank skived to a thin edge. The center portion of the blank in the matrix 34 passes over the knife 16 and is not operated upon.

In the illustrated machine pressure fingers 38 are arranged to press the blank into the matrix 34 there being a number of such fingers 38 in the illustrated machine which engage the blank and a number of other fingers at each side thereof, so that matrix rolls having matrices of dif-

ferent widths may be used in the machine without the necessity of changing the fingers 38.

The fingers are pivoted on a horizontal axis or shaft 40 extending laterally of the machine parallel to the axes of the rolls 12 and 14 and in front thereof. The shaft 40 is secured in a bracket 42 which is fastened to the machine frame 10 by means of guideways 110 and bolts 44 and 46 (Fig. 2). Each finger 38 has an operating portion 5 which extends rearwardly of said shaft 40 and is positioned in a groove 46 (Fig. 1) extending around and formed on the feed roll 14 and a forwardly extending portion 48 which is held down by a tension spring 50 connected at the upper end to the finger and at the lower end to a depending portion 52 of the bracket 42. Each finger portion 48 is provided with an adjustable screw member 54 arranged to bear down upon a lip 56 of a supplementary lever 58 pivoted on the shaft 40 thereby constituting a means for maintaining each supplementary lever and its pressure finger in adjusted relation. As spring 50 pulls finger portion 48 downwardly the screw member 54 serves to push the supplemental lever 58 down against a cam control member or finger controlling cylinder 60. Each supplementary lever 58 is provided with a contact member 62 to take the pressure between the lever 58 and the control cylinder 60 for an effective and sensitive control. The control cylinder 60 is rotatably mounted by means of a shaft 69 in the brackets 71 and 73 held to the guideways 110 by bolts 75 and 77. The cylinder 60 is parallel to the matrix and feed rolls, and is driven in timed relation thereto by means of sprockets 64, 66 and chain 68 (Fig. 2). The fingers 38 are spaced apart about one-eighth of an inch and the surface of the feed roll 14 between the fingers is roughened to assist in feeding the blank to the knife 16.

40. The finger controlling cylinder 60 has formed in it a depression 70 corresponding substantially to the shape of the matrix 34 and has a concentric cylindrical portion between the ends of the depression and at each side thereof.

45. The arrangement is such that when the contact members 62 are in engagement with the cylindrical portions of the control cylinder 60 the work engaging portions of the fingers 38 which are immediately in front of the knife edge are just

50. out of engagement with the cylindrical portions of the matrix roll 12 and when any of the members 62 are in engagement with the depression 70 in the control cylinder, the work engaging portions of those fingers may, if no work is in the machine, rise into or within the matrix 34 but not into engagement with the bottom of the matrix—i. e., the range of operation of the fingers may extend within the matrix. The depression 70 in the control cylinder 60 is so arranged that

55. the fingers 38 controlled thereby are not allowed to rise until the leading edge of the blank has passed between the rolls 12 and 14 but are allowed to rise before the knife cuts out of the blank material so that during this cutting out of the knife the blank is held firmly against the matrix 34 and tearing of the blank is avoided. The fingers 38 are free to be raised by their springs 50 until the trailing end of the blank is just passing to the knife 16. The action of the

60. fingers 38 is then so modified or controlled by the control cylinder 60 that the work engaging portions of the fingers are again held just out of engagement with the cylindrical portion of the matrix roll 12. The fingers at each side of those engaged by the depression 70 in the control

cylinder will, of course, be held out of engagement with the matrix roll 12 all the time the blank is being operated upon and also while the rolls are rotating idly. Each member 62 will follow a contour of the cylinder 60 and thus neutralize the action of a spring 50 for modifying the movement of a finger 38 to follow the matrix roll contour with a clearance being maintained between the pressing surface of the finger and the roll 12.

The springs 50 which hold the forward end portions 48 of the fingers down against the control cylinder 60 are independently adjustable by means of pins 76 and nuts 78 (Fig. 1) so that, if desired, some of the fingers such as those which engage the center portion of the blank, may be urged against the blank with greater pressure than those which engage the marginal portion of the blank. While no work is being passed through the machine it can be easily seen that one finger 38, one supplementary lever 58 and one contact member 62 will move as a unit. All the units may be said to constitute a "pressure finger means."

The aforesaid bracket 42 on which the fingers 38, supplementary levers 58, and springs 50 are mounted, may readily be removed from the machine frame 10 to allow the fingers 38 to be changed, and this bracket 42 has rotatably mounted in it an eccentric shaft 80 (Figs. 1 and 4) which may be rotated by the operator to cause the rear end portions 48 of the fingers to be raised and their forward end portions to be lowered in their grooves 46 when it is desired to adjust parts of the machine which cannot readily be seen or reached when they are in operative position. A U-shaped member 82 (Figs. 1, 4) is vertically slidable within the frame member 42 (and by cam action of the shaft 80) is arranged to slide upwardly and bear against the bottom edges of the finger portions 48 as well as the supplementary levers 58 to lift them.

The control cylinder 60 may have a smooth cylindrical outer surface, as shown in Fig. 1, or it may be preferred to use a modified control cylinder 90 such as shown in Fig. 7 on which is provided a projecting portion 92 arranged just in front, considered in the direction of rotation of the roll, of the depression 94. Such an arrangement will cause the fingers 38 to be depressed away from the matrix roll 12 just as the leading edge of the blank is about to enter the bite of the rolls so that the fingers 38 will not possibly interfere with the entry of the blank between the rolls.

It is to be understood that the machine may be provided with any one of various types of conventional magazine feeders by means of which a stack of blanks may be conveniently held on a platform 96 of the machine and by means of which the bottom blank may be fed to the bite of the rolls 12 and 14 in timed relation to their rotation. Figs. 1, 5 and 6 show such a feeding mechanism having space for a stack of blanks 98 to be retained by spring arms 100, 102. A reciprocating feed member 104 is arranged to feed the bottom blank in the stack to the bite of the rolls 12 and 14, this feed member 104 being operated in proper timed relation to the rotation of the rolls by means not shown.

The work engaging portions of the fingers 38 may be adjusted horizontally toward or away from the knife edge and the bite of the rolls 12 and 14 by means of adjustment screw members 106 (Fig. 2) freely mounted in bosses 108 integral

with side members 43 and 45 fastened by screws as shown to the frame 42. Screw members 106 may be turned in or out from the guideways 110 attached to the machine frame by bolts 44 and 46.

We have found that the skived end portions of a stiffener blank which has been skived in a machine having fingers controlled in the manner hereinbefore described are appreciably more uniform than end portions of blanks which have been skived in machines heretofore constructed. It will be realized that, in a completed stiffener it is desirable that the end portions shall be at least substantially uniform, otherwise a boot or shoe in which such a completed stiffener is incorporated may not be of uniform appearance at each side of the heel end portion of the boot or shoe or non-uniform end portions may interfere somewhat with the proper molding of the stiffener.

Having thus described our invention, what we claim as new and desire to secure by Letters Patent of the United States is:

1. A machine of the class described having, in combination, a knife, a feed roll and a matrix roll for feeding a blank between them to the knife, a series of pressure fingers pivotally mounted on an axis for pressing the blank toward the matrix roll at the line of feed, yielding means to provide the said pressure, a supplementary lever for each pressure finger, means for maintaining each supplementary lever in adjusted relation to the corresponding pressure finger, and means to neutralize the said pressure through the supplementary levers.

2. A machine of the class described having, in combination, a knife, a feed roll and a matrix roll for feeding a blank between them to the knife, a series of pressure fingers for pressing the blank toward the matrix roll at the line of feed, yielding means to provide the said pressure, and a rotatable control cylinder with a depression corresponding to the matrix of the matrix roll, said control cylinder being rotatable with the feed roll and operably arranged to neutralize the said pressure in accordance with the contour of the control cylinder and depression.

3. A machine of the class described having, in combination, a knife, a pair of cooperating rolls for feeding blanks to said knife, mechanism including a series of fingers for pressing a blank toward one of said rolls, and means for operating said fingers to effect the pressure in timed relation with the feeding of the blank, said mechanism being removably mounted as a unit on the machine frame.

4. A machine of the class described having, in combination, a knife, a pair of cooperating rolls for feeding blanks to said knife, mechanism including a series of fingers for pressing a blank toward one of said rolls, and means for operating said fingers to effect the pressure in timed relation with the feeding of the blank, said mechanism being adjustable toward and from the bite of the rolls on the machine frame.

5. A machine of the class described having a main frame, a knife fixed to said frame, a pair of cooperating rolls for feeding blanks to said knife, means for feeding individual blanks to said rolls, mechanism including a series of fingers for pressing a blank toward one of said rolls, and means for operating said fingers to effect the pressure in timed relation with the feeding of the blank, said series of fingers being mounted on a bracket slidable with relation to said frame and adapted to be fixed thereto.

6. A machine such as set forth in claim 3, the

said mechanism also including a supplementary lever for each pressure finger, means for maintaining each supplementary lever in adjusted relation to the corresponding pressure finger, and means for operating the fingers comprising a cam member rotatable with one of the cooperating rolls for modifying the action of the fingers through the supplementary levers.

7. A machine of the class described having, in combination, a matrix roll, a cooperating roll, a knife arranged along the discharge side of the bite of said rolls, pressure fingers operating in grooves of said cooperating roll, yielding means tending to move the fingers toward the matrix roll and within the matrix, and power means for maintaining a clearance between the fingers and the matrix roll.

8. A machine of the class described having, in combination, a matrix roll, a cooperating roll, a knife arranged along the discharge side of the bite of said rolls, pressure fingers operating in grooves of said cooperating roll, yielding means tending to move the fingers toward the matrix roll, a control cam member mounted for rotation with the said cooperating roll, and means for limiting the motion of the fingers toward the matrix roll, said limiting means being in contact with the control cam member.

9. A machine of the class described having a main frame, a matrix roll, a cooperating roll, a knife arranged along the discharge side of the bite of said rolls, pressure finger means operating in grooves of said cooperating roll, yielding means tending to move the finger means toward the matrix roll, and cam means mounted for operation in timed relation with the operation of the matrix roll for maintaining a clearance between the finger means and the matrix roll contour.

10. A machine of the class described having, in combination, a matrix roll, a cooperating roll, a knife arranged along the discharge side of the bite of said rolls, pressure finger means for pressing a blank toward the matrix roll, yielding means to provide the said pressure, and power means for maintaining a clearance between the finger means and the matrix roll contour, said power means being provided with cam means for momentarily moving the finger means from the path of a moving blank to facilitate the entrance of the leading end of said blank.

11. A machine of the class described having a main frame, a matrix roll and a cooperating roll on said main frame, a knife arranged along the discharge side of the bite of said rolls, a magazine feeder for feeding individual blanks to said bite, pressure fingers pivoted on an axis for pressing a blank, while being fed, toward the matrix roll, yielding means to provide the said pressure, a supplementary lever for each pressure finger rotatable therewith on the same axis, means for maintaining each supplementary lever in adjusted relation to the corresponding pressure finger, and a control cylinder having a depression corresponding to the matrix of the matrix roll and being rotatable with said cooperating roll and in timed relation with the rotation of the matrix roll, said supplementary levers being in contact with said control cylinder whereby the range of action of the pressure fingers may be modified by the control cylinder contour.

12. A machine of the class described having, in combination, a knife, a feed roll and a matrix roll for feeding a blank between them to the knife, a series of pressure fingers for pressing the blank toward the matrix roll approximately at the line of feed, yielding means to provide the said pressure, and means for maintaining a clearance between each pressure finger and the matrix roll, the range of operation of each pressure finger extending within the matrix of the matrix roll.

13. A machine of the class described having, in combination, a knife, a feed roll and a matrix roll for feeding a blank between them to the knife, a series of pressure fingers for pressing the blank toward the matrix roll approximately at the line of feed, adjustable yielding means to provide the said pressure, and means for maintaining a clearance between the pressure fingers and the matrix roll, the range of operation of some of the pressure fingers extending within the matrix of the matrix roll.

14. A machine as described in claim 13, the means for maintaining a clearance being adjustable exterior to the machine.

LESLIE HUGH BENNION.
WILLIAM ARNOLD SMART.
